(57) **CLAIM**

The ornamental design for a pair of motorcycle handle bar risers, as shown and described.

DESCRIPTION

FIG. 1 is a right frontal perspective view of a pair of motorcycle handle bar risers showing my new design, the left frontal perspective view being a mirror image;

FIG. 2 is a right rear perspective view thereof, the left rear perspective view being a mirror image;

FIG. 3 is a side elevational view thereof, the opposite side being a mirror image;

FIG. 4 is a front elevational view thereof;

FIG. 5 is a rear elevational view thereof; and,

FIG. 6 is a top plan view thereof.

The broken line showing of the portion of a handle bar and of the circular elements is for illustrative purposes only and forms no part of the claimed invention.
